(57) **CLAIM**

The ornamental design for a beverage bottle, as shown and described.

DESCRIPTION

FIG. 1 is a front perspective view of an embodiment of a beverage bottle in the present invention.

FIG. 2 is a bottom perspective view thereof.

FIG. 3 is a front view thereof.

FIG. 4 is a rear view thereof.

FIG. 5 is a top view thereof.

FIG. 6 is a bottom view thereof.

FIG. 7 is a left side view thereof.

FIG. 8 is a right side view thereof.

FIG. 9 is a front perspective view of another embodiment of a beverage bottle in the present invention.

FIG. 10 is a bottom perspective view thereof.

FIG. 11 is a front view thereof.

FIG. 12 is a rear view thereof.

FIG. 13 is a top view thereof.

FIG. 14 is a bottom view thereof.

FIG. 15 is a left side view thereof.

FIG. 16 is a right side view thereof.

FIG. 17 is a front perspective view of yet another embodiment of a beverage bottle in the present invention.

FIG. 18 is a bottom perspective view thereof.

FIG. 19 is a front view thereof.

FIG. 20 is a rear view thereof.

FIG. 21 is a top view thereof.

FIG. 22 is a bottom view thereof.

FIG. 23 is a left side view thereof.

FIG. 24 is a right side view thereof.

FIG. 25 is a front perspective view of still another embodiment of a beverage bottle in the present invention.

FIG. 26 is a bottom perspective view thereof.

FIG. 27 is a front view thereof.

FIG. 28 is a rear view thereof.

FIG. 29 is a top view thereof.

FIG. 30 is a bottom view thereof.

FIG. 31 is a left side view thereof; and,

FIG. 32 is a right side view thereof.

The broken lines in the drawings are for illustrative purposes only, and form no part of the claimed design.

The beverage bottle in the present invention is a liquid container that can contain beverage liquids.
